(57) **CLAIM**

The ornamental design for a chair, as shown and described.

DESCRIPTION

1.1: a first perspective view of the chair.

1.2: a second perspective view thereof.

1.3: a third perspective view thereof.

1.4: a front elevational view thereof.

1.5: a rear elevational view thereof.

1.6: a top plan view thereof.

1.7: a bottom plan view thereof.

1.8: a right side elevational view thereof.

A left side elevational view of the chair is omitted because it is a mirror image of the right side elevational view; the parallel thin lines on the surfaces of the chair represent only shading and do not illustrate ornamentation or decoration; the thin lines on the surface of the chair are ridgelines to specify the shape of the solid surfaces.
